UNITED STATES PATENT OFFICE.

HERMAN L. BEE, OF WEBSTER SPRINGS, WEST VIRGINIA.

RAILWAY-TIE.

,225,751.

Specification of Letters Patent. Patented May 15, 1917.

Application filed February 28, 1917. Serial No. 151,533.

To all whom it may concern:

Be it known that I, HERMAN L. BEE, a citizen of the United States, residing at Webster Springs, in the county of Webster 5 and State of West Virginia, have invented certain new and useful Improvements in Railway-Ties, of which the following is a specification, reference being had to the accompanying drawings.

This invention relates to certain improvements in railway ties and has relation more particularly to a device of this general character of a metallic type; and it is an object of the invention to provide a railway tie having novel and improved means whereby the tie is effectively maintained in applied position.

It is also an object of the invention to provide a novel and improved railway tie which is substantially hollow together with means whereby ballast may be tamped within the tie directly under the rails resting thereon and wherein the intermediate portion of the tie is unfilled in order to increase the cushioning or resiliency of the tie.

The invention consists in the details of construction and in the combination and arrangement of the several parts of my improved tie whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein—

Figure 1 is a view partly in elevation and partly in section illustrating a tie constructed in accordance with an embodiment of my invention, the rails resting thereon being also shown in section;

Fig. 2 is a view in top plan of my improved tie as herein embodied with one of the fastening plates omitted; and

Fig. 3 is a view in bottom plan of my improved tie as herein disclosed.

My improved tie as herein embodied is preferably formed of boiler steel. The longitudinal margins of the metallic plate 1 are bent downwardly, as indicated at 2, to afford the sides of the tie and the opposite ends of the flanges are separated from the plate 1 so that the same may be bent inwardly, as in-

dicated at 3, to form the ends of the tie. The opposite end portions of the plates 1 are also bent downwardly, as at 4, and overlie the inturned portions 3 of the flanges 2 in order that the ends of the ties may have a maximum of strength. The overlying portions 3 and 4 are suitably connected one to the other as indicated at 5.

Connecting the side flanges 2 of the tie are the transversely disposed straight brace irons 6 positioned at a point inwardly of the opposite ends of the tie so as to be positioned directly beneath the rails R resting upon the tie. The central portion of the tie is also provided with the additional straight bracing irons 7 disposed transversely thereof and spaced apart a predetermined distance longitudinally of the tie.

At opposite sides of each of the brace irons 6 are the substantially U-shaped irons 8 having their bases oppositely directed and their free end portions suitably secured to the side flanges 2 of the tie. The base portion of the inner iron 8 is secured directly, as indicated at 9, to the adjacent iron 7.

The side flanges 2 at opposite sides of each of the irons 6 but inwardly of the irons 8 are provided with the elongated openings 11 which afford means whereby ballast may be tamped within the tie and so that the plate 1 of the tie intermediate the irons 8 will rest directly upon the ballast. It will be understood that the space between the inner irons 8 is not filled with ballast and which results in the tie possessing a maximum of resiliency.

The rails R are maintained in applied position upon the tie in any desired manner but as herein disclosed, I employ the plates 95 12 detachably secured to the plate 1 and overlying the outer flanges of the rails. Interposed between the rails R is the member 14 also suitably engaged with the plate 1 and which has its opposite end portions co-acting with the inner flanges of the rail.

I do not wish to be understood in any way as limiting myself to the character of rail fasteners to be employed and reserve to myself the right to employ any means which may be used with facility.

From the foregoing description, it is thought to be obvious that a tie constructed in accordance with my invention is of an extremely simple and comparatively inexpensive nature and is particularly well adapted for use by reason of the conven-

ience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. A metallic railway tie comprising a plate and depending marginal flanges, brace members interposed between the longitudinal marginal flanges at a point beneath the rail seats, and additional members interposed between the longitudinal marginal flanges of the tie at opposite sides of each of the first named braces, the longitudinal marginal flanges being provided with openings at opposite sides of each of the first named braces and inwardly of the second named braces at opposite sides thereof, said second named braces being substantially U-shaped in form with their bases oppositely directed.
  2. A metallic railway tie comprising a plate and depending marginal flanges, brace members interposed between the longitudinal marginal flanges at a point beneath the rail seats, and additional members interposed between the longitudinal marginal flanges of the tie at opposite sides of each of the first named braces, the longitudinal marginal flanges being provided with open-
- ings at opposite sides of each of the first named braces and inwardly of the second named braces at opposite sides thereof, said second named braces being substantially U-shaped in form with their bases oppositely directed, the base portions of the outer second named braces being secured to the end flanges of the tie.
3. A metallic railway tie comprising a plate and depending marginal flanges, brace members interposed between the longitudinal marginal flanges at a point beneath the rail seats, additional members interposed between the longitudinal marginal flanges of the tie at opposite sides of each of the first named braces, the longitudinal marginal flanges being provided with openings at opposite sides of each of the first named braces and inwardly of the second named braces at opposite sides thereof, said second named braces being substantially U-shaped in form with their bases oppositely directed, and additional brace members interposed between the longitudinal marginal flanges of the tie at the central portion thereof, the bases of the inner of the second named brace members being secured to said last named members.

In testimony whereof I hereunto affix my signature in the presence of two witnesses.

HERMAN L. BEE.

Witnesses:

J. M. HOOVER,
J. B. SKIDMORE.
